UNITED STATES PATENT OFFICE

ALEXIS SZABO, OF CLUJ, RUMANIA, ASSIGNOR OF ONE-HALF TO DAVID SCHOBEL, OF NEW YORK, N. Y.

WATER VEHICLE

Application filed August 2, 1929, Serial No. 382,905, and in Rumania June 27, 1929.

This invention relates to improvements in water vehicles and has particular reference to a manually propelled apparatus.

An object of the invention is to provide an improved vehicle of simple and practical construction which may be used for water sports and wherein means are employed for enabling the operator to propel and steer the vehicle in the water.

10 Another object is to support from a buoyant body a propelling means which may be controlled from the seat of the vehicle and to provide a foot actuated steering mechanism also operable from said seat.

15 The above and other objects will appear more clearly from the following description, when taken in connection with the accompanying drawing, which illustrates preferred embodiments of the inventive idea.

20 In the drawing:

Fig. 1 is a side elevation of one form of the vehicle constructed in accordance with the invention.

Fig. 2 is a top plan view thereof.

25 Fig. 3 is a section on the line 3—3 of Fig. 1, and

Fig. 4 is a fragmentary view, similar to Fig. 1, showing a different form of propelling means.

30 Referring more particularly to Figs. 1 to 3, the body of the vehicle is shown as comprising a pair of elongated buoyant members 5 to which is secured, by means of straps 6, the longitudinally extending seat member

35 7 having a back rest 8 adjacent its rear end and the ornament 9 at its front end. At the front end of the body, the same is provided with laterally extending stabilizers 10 which 40 add to the buoyancy of the body and assist in maintaining the same on an even keel in the water.

45 Depending from the body intermediate its ends is a frame consisting of the vertical pieces 11 which are connected adjacent their

upper ends by cross braces 12 and at the lower ends by the keel 13.

The propelling mechanism comprises a shaft 14 journaled in any suitable manner in the pieces 11 and having a propeller 15 at its rear end. Either at the forward end of said shaft, or otherwise conveniently supported by the frame, is a weight 16 which will, at least, partially counter-balance the weight of the person seated on the vehicle 55 so that the latter will be maintained on an even keel longitudinally. A large gear 17 is supported for rotation by the rear piece 11 of the frame and meshes with a small gear 18 on the propeller shaft. To drive said 60 gearing, there is provided an operating handle lever 19 pivoted intermediate its ends to the braces 12 and having its upper end projecting through a slot 20 in the seat 7 so as to be within easy reach of the operator. The 65 lower end of the lever 19 is connected, by a pitman 21, to the gear 17 so that when the lever is oscillated said gear will rotate and impart a similar movement to the shaft 14, thereby propelling the vehicle through the 70 water.

The steering mechanism for the vehicle comprises a rudder 22 supported at the rear end of the seat 7 and connected on either side, by flexible elements 23, to an operating lever 24 pivoted intermediate its ends to the front piece 11 and arranged so that the operator may place his feet upon said lever and by a pressure with either foot turn the rudder in the desired direction. 75

In Fig. 4, the propelling means is shown as comprising a paddle wheel 25 mounted upon the rear end of the seat 7 and connected to the sprocket gear 26 by the endless chain 27. The gear 26 replaces the gear 17 of Fig. 85 1 and is driven in the same manner as the latter gear to impart rotation to the paddle wheel 25.

What is claimed is:

A water vehicle comprising an elongated 90

seat-board, buoyant members secured to the under face thereof and extending throughout the length thereof, a frame carried by the seat-board and depending therefrom, a balancing keel carried by the lower end of said frame, propelling means for said vehicle, means carried by said frame for driving said propelling means, said driving means including a shaft, and a counterbalancing weight carried by the forward end of said shaft.

In testimony whereof I have affixed my signature.

ALEXIS SZABO.
